[57] CLAIM

The ornamental design for an anti-glare visor for computer terminal, as shown and described.

DESCRIPTION

FIG. 1 is a top, front, right side perspective view of an anti-glare visor for computer terminal.

FIG. 2 is a top plan view thereof;

FIG. 3 is a left side elevational view thereof, the right side elevational view being a mirror image;

FIG. 4 is a front elevational view thereof;

FIG. 5 is a rear elevational view thereof; and

FIG. 6 is a bottom plan view thereof.
